FOOD CHOPPER

Hans E. A. Rable, Philadelphia, Pa., assignor to
The Enterprise Manufacturing Company, of
Pennsylvania, Philadelphia, Pa., a corporation
of Pennsylvania

Application July 13, 1938, Serial No. 219,085

3 Claims. (Cl. 146—182)

This invention relates to food choppers and, more particularly, to food choppers of the commercial or motor-driven type.

The usual type of food chopper comprises a chopper casing having a barrel within which is arranged a scroll or worm by means of which the food to be cut is fed to a perforated chopper plate and its coating knife. Obviously, this worm exercises considerable thrust in the direction of its length when in use, and for this reason it is usual to provide at the shank end of the scroll a bearing for engagement against the wall of the barrel through which this shank end is directed. It is also well known that the shafts of motors, and particularly motors of the heavy-duty type, have considerable axial movement and, for this reason, such motors have, in most instances with which I am familiar, been connected through a train of gearing eliminating possibility of end thrusts through axial movement of the armature shaft.

An important object of this invention is the provision of a novel structure through which the motor and scroll may be directly connected without the necessity of providing means for holding the shaft of the motor against end movement or of providing a bearing for the shank end of the scroll, and in which, at the same time, all possibility of transmission of end thrusts by either of these elements to the other is completely eliminated.

Another object of the invention is the provision of means for mounting a thrust bearing in such fashion that it will accommodate the thrusts of both elements while maintaining them in proper alignment, and in which full lubrication for the thrust bearing may be provided and all possibility of either the lubricant for the bearing or juices exuded from the chopper arriving at locations where they can result in damage either to the bearing or the food in the chopper is completely eliminated.

A further object of the invention is the provision of a structure of this character which may be very readily cleansed, may be very readily disassembled for inspection and repair, and which will be durable and efficient in service.

These and other objects I attain by the construction shown in the accompanying drawings wherein, for the purpose of illustration, I have shown a preferred embodiment of my invention, and wherein:

Fig. 1 is a side elevation, partially in section, of a food chopper constructed in accordance with my invention;

Fig. 2 is an enlarged sectional view through the mounting for the connection between the armature shaft and the scroll; and

Fig. 3 is a section on line 3—3 of Fig. 2.

Referring now more particularly to the drawings, the numeral 10 indicates a suitable base upon which is securely mounted a motor M having an output shaft 11. This shaft extends into an opening 12 formed in a standard 13 arising from the base. The standard 13 is formed in two sections, one of which is preferably integral with the base, as illustrated, and the other of which comprises a retaining and closure plate 14 removably secured to the main body of the standard as by screws 15, and adapted, as at 16, for attachment thereto of a casing 17 of the chopper proper.

The casing 17 comprises the usual barrel 18 containing a scroll 19 for feeding material to a perforated plate 20 and its associated cutting knife 21. This scroll has a shank end 22 extending freely through an opening 23 in the standard-confronting end of the barrel and this shank end is equipped with a polygonal tip 24. The standard affords an annular socket 25 seating the outer race element 26 of a thrust bearing locked in position by the plate 14, the inner race element 27 of this thrust element mounting a stub shaft 28 which has at one end a head 29 abutting the inner race element and at its opposite end a connecting element 30 at present shown as in the form of a sleeve which is rigidly secured thereto and abuts the opposite face of the inner race element of the thrust bearing. This sleeve has a splined connection as at 31 with the output shaft of the motor permitting axial movement of the armature shaft, as suggested by the construction lines at 32 in Fig. 2. The head 29 has a socket 33 receiving and conforming in shape to the polygonal tip 24 of the scroll shank, this tip bottoming in the socket so that possible end movement of the scroll is prevented.

The plate 14 affords an annular chamber 34 about this head, one end of which is defined by the end wall 35 of the barrel, this chamber having a bottom drain opening 36 and an upper opening 37 closed by a hinged gate 38 through which a hose may be inserted for flushing out the chamber 34. The opposite wall of the chamber surrounds the inner end of the head and has an annular channel 39 confronting this head, the head being formed with throw rings 40 at opposite sides of the channel so that any liquids moving along the head will be thrown from the 55

head and into channel 39. This channel has a bottom discharge opening 41 at present shown as dumping into the lower discharge opening 36 of chamber 34. The standard further provides, in spaced relation to the inner end of the thrust bearing, a wall 42 through which the connecting member 30 is rotatably directed, this wall being spaced from the bearing to provide a lubricant channel 43 and having sealing engagement with the exterior of the connecting element as by means of a packing 44.

It will be noted that since the stub shaft 28 is locked against end movement with relation to the thrust bearing, all thrust of the screw will be taken up by this thrust bearing and, since the scroll has socket engagement with the head of the stub shaft, the scroll will be held accurately centered and any end wear thereon as a result of feeding thrust will be avoided. It will be obvious that the output shaft of the motor can exercise no end thrust since it is simply floating in the connecting member 30 and, therefore, no damage to either element as a result of the direct connection will result. It is also obvious that through the throw rings 40 possibility of lubricant reaching the chopper chamber is eliminated, and through the head and said rings any possibility of juices exuding from the chopper barrel through opening 23 reaching the bearing will likewise be eliminated. Furthermore, it will obviously be possible to remove the scroll 19 simply by removing the ordinary retaining ring 45 and withdrawing the scroll through the larger end of the chopper barrel, thus facilitating thorough cleansing of the apparatus, particularly when this feature is considered in conjunction with the flushing arrangement provided for channel 34.

Since the construction is, obviously, capable of a certain range of change and modification without departing from the spirit of my invention, I do not wish to be understood as limiting myself to the particular structure illustrated except as hereinafter claimed.

I claim:

1. In a food chopper or the like, a base, a motor on the base and including an output shaft, a standard on the base, a grinder casing supported by said standard, a scroll in said casing and having a polygonally tipped shank freely extend-

ed through an opening in the standard-confronting wall of the casing, a thrust bearing in said standard and including inner and outer race elements, a stub shaft mounted in said bearing and having at one end a head socketed for the reception of the tip of said shank and at its opposite end a connecting element splined to the output shaft of the motor, said connecting element being fixed to said stub shaft and said connecting element and said head abutting opposite faces of the inner race element of the bearing.

2. In a food chopper or the like, a base, a motor on the base and including an output shaft, a standard on the base, a grinder casing supported by said standard, a scroll in said casing and having a polygonally tipped shank freely extended through an opening in the standard-confronting wall of the casing, a thrust bearing in said standard and including inner and outer race elements, a stub shaft mounted in said bearing and having at one end a head socketed for the reception of the tip of said shank and at its opposite end a connecting element splined to the output shaft of the motor, said connecting element being fixed to said stub shaft and said connecting element and said head abutting opposite faces of the inner race element of the bearing, means to supply lubricant to said bearing, the standard affording a discharge chamber surrounding the head and means on said head for deflecting liquids moving along said head to said discharge member.

3. In a food chopper or the like, a base, a motor on the base and including an output shaft, a standard on the base, a grinder casing supported by said standard, a scroll in said casing and having a shank freely extended through an opening in the standard-confronting wall of the casing, a thrust bearing in said standard and including inner and outer race elements, a stub shaft mounted in said bearing and having means engaging opposite ends of the inner race element preventing relative axial movement thereof with relation to the stub shaft, a splined connection between the output shaft and one end of said stub shaft, the scroll shank having its end abutted against the opposite end of the stub shaft, and means preventing relative rotation of the scroll and stub shaft.

HANS E. A. RABLE.
